Attorney.

UNITED STATES PATENT OFFICE.

CHARLES F. BIERBACH, OF MILWAUKEE, WISCONSIN, ASSIGNOR TO ALBERT G. BIERBACH, OF SAME PLACE.

FIRE-ESCAPE.

SPECIFICATION forming part of Letters Patent No. 278,810, dated May 29, 1883.

Application filed February 7, 1883. (No model.)

To all whom it may concern:

Be it known that I, CHARLES F. BIERBACH, a citizen of the United States residing at Milwaukee, in the county of Milwaukee and State of Wisconsin, have invented certain new and useful Improvements in Fire-Escapes; and I do hereby declare the following to be a full, clear, and exact description of the invention, such as will enable others skilled in the art to 10 which it appertains to make and use the same, reference being had to the accompanying drawings, and to letters or figures of reference marked thereon, which form part of this specification.

15 My invention relates to improvements in that class of fire-escapes which are permanently attached to the exterior walls of a building by a tramway, upon which it is adapted to be easily and quickly moved to all places of exit 20 along the exterior walls of a building, which improvements are further explained by reference to the accompanying drawings, in which—

Figure 1 represents a perspective view of a building provided with my escape. Fig. 2 25 represents a cross-section of the supporting-tramway and a side view of one of the attachments by which the ladder is connected therewith. Fig. 3 represents a longitudinal section of the tramway and a front view of the 30 upper end of the ladder. Fig. 4 represents a perspective view of a shield for protecting the tramway. Figs. 5 and 6 are details.

Like parts are represented by the same reference-letters throughout the several views.

35 My tramway is formed of a tube, A, which is provided with a slot, B, on its lower side for the reception of the hangers C C. The tramway is rigidly and permanently secured to the walls of the building by brackets D, and 40 when desired the tramway may be extended in one continuous line entirely around the building, in which case the tube A is gradually curved around all the corners or angles, so that the supporting-rollers E E will be free to 45 traverse such parts of the tramway. The sides of the ladder F F are preferably formed of wire cable, and the steps or rounds are formed of metal bars or rods. The rollers E E are made spherical in shape, to conform to 50 the interior surface of the tube upon which

they are adapted to roll as the ladder is moved. The rollers E respectively consist in two parts, a a, which are connected together by the axis J. Slides may, if desired, be substituted for the rollers E. The parts a a are adapted to roll upon the respective sides of the slot B while the hangers are moved through said slot. The axes J are inserted through and are adapted to revolve in the said hangers as the rollers and ladder are moved along said tramway. 55

To facilitate in turning a curve in the tramway the upper round, K, of the ladder is formed in two pieces connected together by a joint, L, which permits the respective sides of the ladder to yield sufficiently to conform to the shape 65 of the tramway without cramping the ladder or obstructing its movement. The supporting-bracket D is provided with a slot, M, corresponding with the slot B in the tube, for the passage of the hangers. 70

N is a binding-screw by which the tube A is prevented from moving in the bracket.

To facilitate in moving the ladder when connected with high buildings, a cord, O, is attached to its upper end, which cord is of 75 sufficient length to reach the ground when drawn at an angle to the ladder, as shown, whereby it is obvious that a more direct lateral force may be applied to the upper part of the ladder, and the same more easily moved than 80 when operated solely at its lower end. The cord O is connected with both sides of the ladder, as shown, by the branch cords b and d, so that the draft upon said cord will always be applied upon the opposite side of the ladder 85 from that toward which the ladder is drawn.

The rounds or steps F of the ladder are covered with an asbestos shield, P, which prevents contact of a person's hands with the heated surfaces of the rounds. 90

The several sections of tubing of which the tramway is composed are connected together by the slotted tube-couplings S. Tare strengthening-collars upon the tubes, to prevent the slot opening where great weight is to be supported.

To provide for the expansion and contraction of the tramway one or more of the sections of the tramway are connected together by the device shown in Fig. 6, which consists 100

in the collar A', provided with slots B' B' and bolts C' C'. The inner ends of the bolts C are secured rigidly into the tube and move with it as the tube expands and contracts, while 5 their outer ends are free to move in the slots C'. The joint thus formed is preferably located in one of the supporting-brackets D and the collar A' is rigidly retained in a fixed position by the screw N, which extends through 10 said bracket and into the exterior surface of said coupling A. It is obvious that when a ladder is thus supported it may be easily and quickly moved past all the places of exit from every story in the building and that there is no 15 possibility of the ladder falling.

In case the building is large, several ladders may be supported upon a single tramway.

To prevent the accumulation of ice or the injurious action of the elements upon the tramway a shield, R, is provided, which is supported upon said tramway and the supporting-brackets, as indicated in Fig. 2.

If desired, the ladder may be suspended from a single roller instead of two; or more 25 than two rollers may be employed, as occasion may require. The ladder may be drawn from one end of a building to the other, in either direction, by cords E' E', operating over pulleys F', located at the respective ends of the tram- 30 way.

Having thus described my invention, what I claim as new, and desire to secure by Letters Patent, is—

1. The combination of a slotted tubular 35 tramway attached to the exterior walls of a building, with the respective sides of a ladder, said sides being inserted through the slot in said tramway and retained therein by rollers or slides, upon which the sides of the ladder 40 are moved, the respective sides of the ladder being adapted to move through said slot and prevented from turning thereby as the ladder is moved, substantially as set forth.

2. The combination of the slotted tubular 45 tramway A, rollers E E, hangers C C, and the respective sides of the ladder F F, said hangers being connected together by a bar, K, as set forth.

3. The combination of the slotted tramway A with the slotted cast-metal bracket D, formed 50 in a single piece, the slot in said bracket being adapted to correspond with the slot in said tramway, whereby the sides of the ladder may pass through said brackets as they move through the slots in said tramway, substan- 55 tially as set forth.

4. The combination, with the solid slotted bracket D and slotted tubular tramway A, of the set-screw N, as set forth.

5. The combination of the slotted tubular 60 tramway A, slotted bracket D, and slotted coupling-collar S, said collars and bracket being adapted to connect together and support said tramway, as set forth.

6. The combination, with the tubular slotted 65 tramway, of the slotted strengthening-collars T, as adapted to strengthen and prevent the tramway from spreading, as set forth.

7. The combination, with the steps of a ladder, of the asbestos covering or shield adapted 70 to prevent contact of a person's hands with their heated surfaces, as set forth.

8. The combination, with the tubular slotted tramway A, of the shield R, as adapted to protect said tramway from the elements, as 75 set forth.

9. The combination, with one or more of the joints of the tubular tramway, of the collar T, provided with slots B' B', screws C' C', bracket D, and set-screw N, said slots B' being adapted 80 to permit of the lateral movement of said screws C' C', as said sections of the tramway expand and contract, substantially as set forth.

10. The combination, with the hangers C C, of the jointed step, as adapted to permit the 85 sides of the ladder to conform to the curves in the supporting-tramway, as set forth.

In testimony whereof I affix my signature in presence of two witnesses.

CHARLES F. BIERBACH.
